SHOEHORN

Edward B. Morgan, Philadelphia, Pa.

Application February 14, 1939, Serial No. 256,340

7 Claims. (Cl. 223—118)

This invention relates to apparel apparatus and more particularly to apparel apparatus of the shoe-horn type.

Heretofore in the manufacture of shoe-horns, it has been a practice in some instances to make the shoe-horn of sheet material. Such horns are frequently rigid and molded to conform generally with the contours of the foot and hence function with nominal efficiency. However, such articles leave much to be desired in points of safety, convenience and suitability. For instance, not only are conventional shoe-horns characterized by sharp areas which cause painful bruises when accidentally stepped on, but the requisite curvature prevents them from packing flat and, in addition to their length, renders them too bulky for carrying on the person. Furthermore, the sharp edges and unyielding structure cause them to catch on the threads of hose causing holes and destructive runs on the latter.

The present invention contemplates a shoe-horn composed of a foot engaging portion consisting of a polished, flexible wire shield permanently retained by a flexible leather pocket or holder. The wire shield may consist of a single strand of serpentine bent wire lying in several aligned lengths and is arranged to be retractible to lie flat in the holder when not in use. When withdrawn to extend beyond the holder, both shield and holder may manually be bent to conform comfortably to the exact curvature of the heel. The wire of the shield is preferably plated to insure smoothness and eliminate possibility of corrosion; and both the shield and pocket are free from sharp or unyielding surfaces.

The invention will be fully understood by referring to the following detailed description, reference being had to the accompanying drawing forming a part thereof, wherein

Fig. 1 is a perspective view of a shoe-horn constituting one embodiment of the invention applied to a conventional shoe fragmentarily shown in broken lines;

Fig. 2 is a plan view, partly in section, of the shoe-horn of Fig. 1, showing in broken lines the shield portion extended to operative position; and

Fig. 3 is a section taken on the line 3—3 of Fig. 2, showing the flexible shoe-horn bent in either direction to conform with the curvature of the shoe.

Referring to the drawing wherein identical parts are indicated by similar reference numerals, the employment of a shoe-horn 10 embodying the invention is indicated in Fig. 1. The horn includes a holder 11 composed of corresponding

leather sheets 12 and 13 assembled with the dressed side 14 out and the undressed side 15 abutting. To form the holder, said leather sheets are formed with slightly flaring edges 16, 16 and each has a straight end 18 and opposite round end 19. The pocket is constructed by binding sheets 12 and 13 together with continuous stitching 20 extending from the straight edge 18 downwardly along edges 16 and round end 19.

An important feature of horn 10 is shield 22 consisting preferably of a single strand of relatively stiff, smooth, heavily plated spring bronze wire 23. By referring to the drawing it will be observed that wire 23 is bent in serpentine fashion to lie flat, opposite ends 24 being curved and protected in the bottom of holder 11, and straight portions 26 between ends 24 lying substantially parallel between curves 27 at opposite ends of the shield.

While the strand 23 is referred to as being wire, it may be of any suitable material and the connecting curved end portions 27 thereof give the shield, as a whole, the flexible resiliency which characterizes the device. By reason of these connecting end portions 27 the relatively straight portions 26 are normally maintained in substantially the same plane and allow the shield 22 to be deformed from its normal flat position to conform under conditions of use as shown in the drawing to the heel of the shoe and the foot and after such use to return the straight portions 26 to their normally flat position or plane.

Referring particularly to Fig. 2, it will be observed that shield 22 in completed form has straight end 28 for reception at the bottom of holder 11 and also has curved end 30 arranged to project at the top beyond holder 11. It will be understood that the pocket and holder correspond as to dimensions to cause the shield to extend entirely across the interior of the holder.

The wire stock employed or the other material which forms the strand 23, is preferably rounded in cross section and has a smooth polished surface, thus enabling the shield 22 to be slidably moved in and out of the holder 11, when desired, and possessing no sharp or ragged edges which may injure the stocking, or by continual use stretch heel of the shoe out of shape, and finally chafe and cut stitching in same and otherwise mar finish of the heel.

The serpentine formation of the shield provides a characteristic resilience and flexibility thereto so that the shield has a moderate tendency to expand laterally thus insuring that it will, at all

times, snugly engage the internal surfaces of the cover and particularly at the edges thereof.

In order to assist in locking the shield in retracted position in the pocket when not in use, the flaring edges 16 are provided. When the wire shield is pushed into the holder the straight portions of the shield are brought closer together for compact storage. For use, the shield may be withdrawn manually to project, as shown in broken lines in Fig. 2, in which position the aligned portions of the shield flare slightly in fan-like manner to provide wider area and greater flexibility for handling in the shoe. In order to prevent dislocation of the shield with respect to the holder or handle 11 and to insure maintenance of the straight portions of the shield in the desired alignment disclosed, holder 11 has a lower guide stitching 32 and parallel upper guide stitching 33 for binding the leather sheets 12 and 13 together between each length of wire. In addition to maintaining the wire lengths in position, stitching 32 and 33 assists in maintaining the shield in the pocket when not in use. Accidental projection of the shield from the pocket is additionally prevented by the undressed character of the inner faces of leather sheets 12 and 13.

The sturdy construction described has been found durable and convenient in operation. The wire shield may easily be withdrawn to project from the holder and in such position its inherent flexibility about the longitudinal axis renders it readily conformable to the individual configuration of the shoe and foot of the wearer. The construction, as indicated in Fig. 3, is flexible in either direction, hence may conveniently be used with either surface exposed. After use the shield may easily manually be pushed into the holder for compact storage, in which condition the holder may conveniently be packed or carried on the person without conspicuous or uncomfortable bulging. Whether the shield is extending or withdrawn into the cover, if it should be cast on the floor and stepped on accidentally, no injury will result because of its tendency to lie flat.

If desired, the materials employed in forming the shield and cover may be of fine quality and attractive appearance such as to be productive of a relatively fine article of merchandise. On the other hand, the characteristics described above are obtainable through the use of cheap materials without loss of the several advantages referred to. Either or both of the outer surfaces of sheets 12 and 13 which may be of any desired material, may be decorated in any desired manner.

By the above description, the shoe horn of this invention is stated as being extensible from and retractable into the sheath or holder 11, but it

is also within the purview of this invention to have the shield or shoe horn, proper, 22 to be fixed in its extended relation to the sheath or holder 11 as shown in Fig. 1. This may be accomplished by any suitable means, such, for one instance, as having the stitches 32 or 33, or both, sufficiently tight as to resist inward movement of the shield 22 into the holder or sheath 11.

I claim:

1. A shoe-horn including a flexible leather pocketed type handle, and a flexible wire shoe-engaging element slidable therein, said handle having a row of stitches for retaining said element in the pocket, and said element having smooth surfaces to facilitate its sliding movement with respect to said stitches. 10

2. A shoe-horn having a handle with a relatively wide end portion and a flexible shoe-engaging element comprising a plurality of spaced resilient bars attached to and extending from said relatively wide end portion of the handle and normally disposed to lie flat in the same plane but bendable freely out of said plane, when used, to conform to configuration of a shoe heel. 15

3. A shoe-horn comprising a handle portion and a plurality of substantially parallel bars attached to said handle portion and resiliently connected together alternately at their opposite ends so as to be biased to normally lie in the same plane and to be yieldably deformed from said plane when used. 20

4. A shoe-horn comprising a strand of material bent in serpentine shape to provide relatively long and substantially parallel bar portions normally lying in the same plane, the portions of the strand connecting the bar portions giving resiliency and flexibility to the horn so that the horn is biased to normally lie substantially flat and is deformed, under conditions of use, to conform to the heel of the shoe and foot. 25

5. A shoe-horn as set forth in claim 4 and wherein there is a flexible handle portion to which said bars are connected by stitches on the handle portion extending between said bars. 30

6. A shoe-horn as set forth in claim 2 wherein the handle portion is of flexible material and said bars are substantially round in cross section and without cornered edges. 35

7. A shoe-horn having a pocketed type handle and a flexible and resilient shoe-engaging element arranged to slide endwise into and out of said pocket, means on said handle for limiting the outward movement of said element from said pocket and for retaining one end of said element within said pocket when said element is 40

in its fully projected position. 50
